UNITED STATES PATENT OFFICE.

FRIEDRICH GRÖSSLER, OF HERMSDORF (RIESENGEbirge), GERMANY, ASSIGNOR TO LINKE-HOFMANN-WERKE A. G. ABTEILUNG FULLNERWERK, OF WARMBRUNN, SCHLESIEN, GERMANY.

WOOD-PULP-GRINDING PLANT AND THE ART OF OPERATING THE SAME.

Application filed February 9, 1928, Serial No. 253,168, and in Germany February 14, 1927.

The invention relates to an improvement in wood pulp grinding plants and in the art of operating the same.

In the operation of wood pulp grinding machines it is an essential requirement that the speed of the prime mover driving the grinding stone be maintained absolutely constant. Numerous disadvantages result from a failure to comply with this requirement, 10 for instance, the impossibility of producing a high grade product because such variations in the speed of the grinding stone as may be caused by a change in the load, affect the quality of the pulp produced.

15 The customary manner of regulating the speed of the prime mover coupled with the grinding stone consists in automatically controlling the energy produced by the prime mover in order to compensate for changes 20 in the load and to keep the speed invariable. Usually mechanical regulators serve for this purpose, particularly, when the prime mover is formed by steam engines, combustion engines or the like. Such mechanical regulators are not sufficiently sensitive to 25 respond without delay to changes in the speed of the grinding stone. A delay in the response, however, results in fluctuations of the speed and experience has shown that these fluctuations amount at least to 10 pct. in the case of a grinding plant driven by a prime mover provided with an ordinary centrifugal regulator.

One object of my invention is the provision 35 of a regulating device by means of which the fluctuations of speed may be kept down below the limit of 1 pct.

Another object of the invention is the provision of a regulating device which responds 40 immediately and without delay to variations in the velocity or speed of the grinding stone or of the prime mover coupled therewith.

From another aspect, an object of the invention is the provision of a method of maintaining the load of the grinding stone constant whereby an invariable speed is insured 45 without requiring a control of the energy developed by the prime mover at its predetermined normal speed. While the invention may be applied to any wood pulp grinder, it is particularly adapted for use in 50 such grinders which have a continuously operating feeding mechanism, such as shown

and described in United States Patent No. 1,652,044.

55 Wood pulp grinders are frequently driven by a hydraulic turbine equipped with a mechanical regulating mechanism which permits an automatic control of the energy produced at normal speed to compensate for 60 changes in the load. Such a mechanism, however, is expensive and complicated. It is desirable, therefore, to render the same dispensable, so that water turbines may be used in which the energy developed at a certain 65 speed need not be varied. As the invention consists in an electrical regulating mechanism, which maintains the load constant, it creates the possibility of installing in grinding plants hydraulic turbines not equipped 70 with the afore-mentioned automatic mechanical regulating mechanism.

75 Further and more specific objects of the invention will appear from the description hereinafter and the features of novelty will be pointed out in the claims. Two embodiments of the invention are illustrated in the accompanying drawing.

Fig. 1 shows in a diagrammatical fashion a grinding plant comprising a water turbine 80 coupled with a grinder of the type shown and described in the Patent No. 1,652,044 which is equipped with an embodiment of the novel regulating mechanism, Fig. 2 shows a similar arrangement.

85 10 indicates the prime mover which, in this instance, is formed by a water turbine, and at 11 the grinding stone of the wood pulp grinder is shown. As the grinder corresponds substantially with that shown and 90 described in the Patent No. 1,652,044, a detailed description thereof may be dispensed with herein. For sake of clearness it may be mentioned, however, that the feeding shaft filled with logs is indicated at 12. The 95 walls of the shaft 12 are formed by feeding screws 13. The feeding screws are rotated by an electromotor 14.

100 The diagrammatically illustrated axle 15' of the water turbine, on which the grinding stone is mounted, is equipped with a pulley 16' driving an electromotor 17 by means of a belt 18. While in the illustrated embodiment the motor is of the commutator type with a shunted field winding, any other 105 electromotor may be used, e. g. a commu-

tator motor having field and armature wound in series.

The feeding means of the grinder, such as the threaded spindles 13, are provided with a controlling mechanism to control the speed with which the wood is fed against the grinding stone. In the embodiment shown in Fig. 1 the controlling mechanism comprises an electromotor 14 which is in driving connection with the spindles 13, and a generator 15 supplying the motor 14 with electric energy. By regulating the degree of energization of the field 16 of the generator 15, the amount of the energy produced and thereby the speed of motor 14 may be varied. The generator 15 is driven by a suitable motor 17, e. g. by a three-phase induction motor connected with a suitable source 18' of a three-phase current.

The field 16 is supplied with current from any suitable source, for instance from a small generator 21 coupled with the generator 15. The intensity of the current circulating through the field 16 is regulated in proportion to the strength of the current developed by the generator 17. While this regulation may be effected by simply supplying the field 16 with the current produced by the generator 17, another more appropriate way is chosen in the illustrated example. Connected with the poles of the generator 17 is an apparatus 24 which contains a variable resistance 25 and means to automatically vary this resistance 25 in proportion to the current supplied to said means from the generator 17. The resistance 25 is inserted in the circuit of the field 16. As the apparatus 24 is well known and available on the market (in Germany it is manufactured by the firm Brown, Boveri & Cie. and on sale under the name "Schnell-regler") and as the same does not form a part of the invention, the description of this construction need not be given herein.

The operation of the embodiment shown in Fig. 1 is as follows:

It may be assumed that, owing to a decrease in load as may be caused by the occurrence of some soft logs in the wood pile, the speed of the turbine 10 tends to increase. The slightest increase, however, e. g. an increase of less than one pct., results in a substantial increase in strength of the current produced by the generator 17. As a consequence, the apparatus 24 reduces the resistance 25 so that the energization of the field 16 is intensified. The generator 15 consequently produces a stronger current than before, thereby speeding up the motor 14. This effect coincides nearly exactly with the increase in velocity of the turbine 10. The increase in velocity, therefore, causes an immediate increase in feedings speed and, thereby, in the load imposed on the grinding stone by the logs so that any further increase in velocity is effectively counteracted.

The embodiment shown in Fig. 2 differs

from the afore-described embodiment in that the power for rotating the spindles 13 is not furnished by a separate motor, as the motor 17', but is derived from the shaft 15' of the grind-stone. A pulley 27 is keyed thereon and connected by means of a belt with a pulley 28 which is diagrammatically shown as coupled with the primary shaft 29 of a hydraulic gear 30. The secondary shaft 31 of this gear is in driving connection with the spindles 13. The ratio of transmission of the gear may be varied by adjustment of a lever 32 journaled at 33 in the housing of the gear.

While any suitable hydraulic gear may be used which permits a continuous regulation of the transmission ratio within the required limits, a gear is preferred which is on sale on the German market under the name "Lauf-Thoma-Getriebe". The adjusting lever 32 is connected with a servo-motor comprising a piston 33 movable in a cylinder 34 filled with oil. Both ends of the cylinder communicate with a second cylinder 35 by means of conduits 36 and 37. A piston valve 38 mounted in the cylinder 35 is provided with a recessed central section 38' the length of which corresponds with the distance between the conduits 36 and 37. The width of the non-recessed ends of the piston 38 corresponds with the width of the conduits 36 and 37. The central part of the cylinder 35 is provided with a port connected to a pipe 39 supplying oil under pressure from some suitable source. The ends of the cylinder 35 communicate with another oil pipe 40 within which a lower pressure prevails than in the pipe 39. On the end of the piston rod of the piston 33 a double-armed lever 41 is pivoted having its lower arm in pin- and slot-connection with the piston rod of the piston valve 38'. The other arm of the lever 41 is also attached by means of pin and slot to an iron core 42 movably supported in a stationary frame 43, which is shown as attached to the cylinders 34 and 35. The core 42 is subjected to the resilient force of a spring 46 and surrounded by a coil 44 supplied with current from a battery 45 or some other suitable source. The circuit formed by the battery 45 and the coil 44 is controlled by the afore-described apparatus 24.

The operation of the arrangement is as follows:

When owing to a decrease in load which may be caused by the occurrence of particularly soft logs, the speed of the axle or shaft 15' tends to increase, the apparatus 24 immediately reduces the resistance 25. Consequently, the current circulating through the coil 44 is increased and the core 42 is drawn to the right against the action of a spring 46, until a new position of equilibrium is reached between the force exerted by the spring 46 and the increased magnetic force. When the valve 38 occupies the position shown in the

drawings, the piston 33 cannot move because both conduits 36 and 37 are closed by the piston valve 38. When, however, the upper end of the lever 41 is moved to the right by the core 42, the lower end will be swung to the left thereby displacing the valve 38. Consequently, the central recess thereof supplied with oil, under pressure will get into communication with the left end of the cylinder 34 while the right end thereof is brought into communication with the return pipe 40. The pressure exerted on the piston 33 from the left moves the same to the right, which movement displaces the adjusting lever 32, and, coincidentally returns the lower end of the lever 41. The movement will continue until the piston valve 38 has been returned into the position illustrated in the drawings. The displacement of the lever 32 to the right changes the transmission ratio of the gear 30 in such a manner as to raise the speed of the shaft 31 whereby the load imposed upon the grinding stone will be increased. This increase in load counteracts the tendency of the turbine 26 to speed up, whereby the velocity of the turbine and the grindstone is maintained constant.

As the piston 38 does not offer any appreciable resistance to the lever 41, it moves immediately in response to a change in intensity of the current developed by the generator 17.

From the foregoing it is apparent that in a broad aspect, the invention may be viewed as a method to develop an electric current in dependence upon the speed of the prime mover, and to utilize this current for influencing the speed with which the wood is fed to the grinding stone. In spite of the absence of any turbine regulator permitting a variation in the energy produced by the water turbine, a constant speed thereof is maintained. Owing to this fact, other machines requiring a uniform speed such as an electric generator for illuminating purposes may be coupled with the water turbine.

What I claim is:—

1. In a wood pulp grinding plant, the combination comprising a prime mover, a grind-

ing stone in driving connection therewith, wood feeding means to press the pulp wood against said stone, a controlling mechanism to control the speed of said feeding means, a generator connected with said prime mover to be driven with a speed proportional to the velocity of said prime mover whereby an electrical current is generated depending in strength upon said velocity, an electric device influenced by said current and operatively connected with said controlling mechanism to cause an acceleration of the feeding speed when said velocity increases whereby any change in said velocity is immediately counteracted.

2. In a wood pulp grinding plant, the combination comprising a water turbine of the type in which the velocity depends upon the load imposed, a grinding stone in driving connection therewith, wood feeding means to press the pulp wood against said stone, a controlling mechanism to control the speed of said feeding means, a generator connected with said water turbine to be driven with a speed proportional to the velocity of said water turbine whereby an electrical current is generated depending in strength upon said velocity, and an electric device influenced by said current and operatively connected with said controlling mechanism to cause an acceleration of the feeding speed when said velocity increases whereby any change in said velocity is immediately counteracted.

3. In the art of operating wood pulp grinding plants including a prime mover, a grinding stone coupled therewith and feeding means to feed wood against said stone, the method of regulating the velocity of the prime mover consisting in generating electric current in dependence on said velocity and using said current for the exclusive control of the speed of said feeding means whereby an increase in said velocity will cause an immediate increase in said feeding speed and, correspondingly, an increased load imposed upon said prime mover.

In testimony whereof I affix my signature.

FRIEDRICH GRÖSSLER.
